UNITED STATES PATENT OFFICE

2,522,056

TRUSS

Nellie Brennan O'Brien, Marshall, Mich.

Application March 26, 1947, Serial No. 737,239

1 Claim. (CL. 128—96)

1

This invention relates to rupture belts and to the cushion elements therefor.

It is an object of the present invention to provide a rupture belt which has a V-dipped portion extending into the area of the rupture and to which the cushions are attached and wherein adequate straps are provided to extend around the inner side of the leg to sufficiently hold the portion in its downwardly extended position over the rupture.

It is another object of the present invention to provide a cushion or pad which fits over the ruptured area wherein the pad will be thicker on the inner side than on the outer side and at its lower end in order to better support the ruptured area and wherein the pad will have a swivel connection with the strap so as to readily adapt itself over the ruptured area.

For other objects and for a better understanding of the invention, reference may be had to the following detailed description taken in connection with the accompanying drawing, in which

Fig. 1 is a front elevational view of my rupture belt with a single pad applied to one rupture.

Fig. 2 is a front elevational view of my rupture belt with two pads applied to the same and showing the V-dip portion reaching downwardly.

Fig. 3 is a rear elevational view of the pad.

Fig. 4 is a front elevational view of the pad looking upon the soft material thereof.

Fig. 5 is a front elevational view of the supporting piece for the pad.

Fig. 6 is a side elevational view of the supporting piece.

Fig. 7 is a cross-sectional view taken on line 7—7 of Fig. 4 and looking in the direction of the arrows thereof and through the completely assembled pad.

Fig. 8 is a front elevational view of the supporting piece of the pad which is used at the left side of the body.

Referring now particularly to Fig. 1, there is shown my rupture truss as applied to a single rupture. This rupture truss comprises a belt 10 of elastic material adapted to surround the body. The ends of this belt are connected to take-up buckles 11 and 12 respectively and these buckles are fastened by connecting members 13 and 14 respectively to an angle shaped clamping plate 15 which fixes the ends of the belt 10 to a pad 16. It will be noted that clamping plate 15 is so cut and that the connecting members 13 and 14 are so connected to the same that the belt will be V-dipped downwardly in the front and over the

rupture. The belt thus permits the pad to reach down to the rupture no matter how low it is and yet permits the belt to be extended high about the back of the person so that it will not slide down over the hips as is customary with belts which do not have this V-dipped portion.

A leg strap 18 is connected to the pad and is extended down along the inner side of the leg and upwardly to the back for connection with the belt 10 as indicated at 19.

Referring now particularly to Fig. 2, there is shown my belt adapted to support two ruptured areas located at opposite sides of the body. The belt 10 of elastic material may be used at both rupture areas and are connected by connecting members 21 and 22 respectively to pads 23 and 24 located at opposite sides of the body. Between the pads there is connected a strip 25 for preventing the separation of the pads from each other. The connecting members 21 and 22 unite with the pads in such a manner as to permit the belt arrangement to dip downwardly so that the pads 23 and 24 can respectively reach low ruptured areas. Elastic straps 26 and 27 respectively extend from the pads 23 and 24 along the inner side of the legs to hold the pads down in place. These straps connect to the raised portions of the belt 10 as indicated at 28.

Referring now particularly to Figs. 3 to 8, there is shown the construction of the pad elements. A single element is provided with a backing member 31 preferably formed of hard rubber and has an annular groove 32 extending around its edge into which a cover 33 is extended to be retained over padding material 34. Wire 35 is wound into the groove 32 whereby to retain the cover 33. To further fix the cover there is extended a metal casing of cup shape as indicated at 36 onto the rear of the backing member 31.

In order that the padding material 34 will be sufficiently raised at the inner and bottom sides of the same, there is provided a shim 37 of tapered formation which is fixed to the backing member 31. This shim is relieved so as to permit center 38 of the cover 33 to be drawn inwardly so as to provide a recess 39 in the center of the pad. The center of the cover 33 is retained by a wire 41. The ruptured area can swell into the recess 39 so that the pad will have a better grip thereupon.

The cup-shaped casing 36 is secured to the backing member 31 by screws 42. The clamping plate 15 is preferably connected to the pad element so that the pad element can rotate 55 relative thereto. A screw 43 is extended through

a sleeve 44 which passes through the clamping plate 15 and enters the backing member 31. The pad can thus rotate relative to the clamping plate 15.

In the bottom end of the backing member 31 is a slot 45 into which a leg strap 18 or 27 for the belt 10 can be extended and secured by a screw 46.

It will now be apparent that the individual pads can be well adjusted over the ruptured area no matter how low the same may be upon the front of the body and that inasmuch as these pads can swivel relative to the clamping plate 15 they can be readily adjusted so as to locate a raised portion of the pad at the lower part of the ruptured area and that there will be provided a raised portion of the pad at the inner side of the ruptured area.

While various changes can be made in the detailed construction, it shall be understood that such changes shall be within the spirit and scope of the present invention, as defined by the appended claim.

I claim:

In a rupture truss, the combination which comprises an oval-shaped hard rubber backing member having an annular groove in the peripheral edge and a slot extended inwardly from one end and spaced from the rear surface thereof, an arcuate shim having a beveled outer surface adjustably mounted on the face of said backing member, a flexible cover positioned over the face of said backing member, a wire for clamping the edge of the cover in the groove of the backing member, means drawing the center of the said cover inwardly toward the face of said backing member, padding providing filling

material between the cover and face of the backing member, a cup-shaped metal casing covering the rear surface of the said backing member and extended over the edge covering the groove with the cover-retaining wire therein, an angular-shaped clamping plate pivotally mounted on said backing member through the said metal casing, a belt having buckles in the ends thereof formed to be positioned around the hips of a patient, said buckles being attached to the ends of the said angular-shaped clamping plate and with the forward side of the belt in which the said clamping plate is positioned extended downwardly, and a strap with one end extended into and secured in the slot in the end of the backing member and with the other adjustably connected to the belt, said strap being adapted to extend around the thigh of a patient on which the belt and pad are positioned.
